COMBINED CLOTHES RACK AND CONTAINER

Marianne Tuteur, New York, N. Y., assignor to Talon, Inc., a corporation of Pennsylvania

Application April 5, 1952, Serial No. 19,199

Term of patent 7 years

(Cl. D33—3)

To all whom it may concern:

Be it known that I, Marianne Tuteur, a citizen of the United States, residing at New York, in the county and State of New York, have invented a new, original, and ornamental Design for a Combined Clothes Rack and Container, of which the following is a specification, reference being had to the accompanying drawing, forming a part thereof.

In the drawing:

Fig. 1 is a front elevational view of a combined clothes rack and container embodying my new design;

Fig. 2 is a top plan view thereof;

Fig. 3 is a rear elevational view thereof;

Fig. 4 is a side elevational view thereof; and

Fig. 5 is a sectional view taken on line 5—5 of Fig. 1 the rack being shown in section and the container in side elevation.

I claim:

The ornamental design for a combined clothes rack and container, substantially as shown.

MARIANNE TUTEUR.
